UNITED STATES PATENT OFFICE.

FRANK SCHORIK, OF CHICAGO, ILLINOIS, ASSIGNOR TO JOSEPH KOSTOHRYZ, OF CHICAGO, ILLINOIS.

FLASH-LIGHT GUN.

Application filed March 18, 1922. Serial No. 544,701.

To all whom it may concern:

Be it known that I, FRANK SCHORIK, a citizen of the United States, residing at Chicago, in the county of Cook and State 5 of Illinois, have invented certain new and useful Improvements in Flash-Light Guns, of which the following is a specification.

This invention relates to an apparatus adapted to hold a limited quantity of flash 10 light powder, and to means associated therewith for igniting the same. It is a primary object of this invention to devise an apparatus of this kind which will be compact in size, inexpensive to produce, and safe and 15 certain in its operation.

An embodiment of my invention in its preferred form is illustrated in the accompanying drawing in the manner following:

Figure 1 is a side elevation of a gun with 20 the side plate removed to exhibit the trigger mechanism;

Fig. 2 is a fragmentary vertical section therethrough exhibiting the trigger parts in the position occupied just prior to kicking 25 off; and

Fig. 3 is a detail in elevation looking toward the rear end of the device.

The major parts of my gun include a powder trough A mounted above a body B 30 from which extends a tube C equipped with a handle D. The trough may be of any suitable size and shape for the reception of a desired quantity of flash light powder and is preferably carried upon a bracket 5 mounted to swivel upon a neck 6 projecting upwardly from the body B, one side of which is covered by a removable plate 7.

The bracket is formed with a transverse bar 8 in spaced relation to the trough bottom 9, and in this intervening space is a plate 10 pivoted at one end 11 so as to swing out from beneath the trough, when desired. In the plate is a central aperture formed to provide a seat 12 for the reception of a powder cap (not shown). The cap seat is in register with a hole 13 extending through the bottom of the trough, and also with an opening 14 in the bracket bar 8 which aligns with a bore 15 extending 45 through the neck 6. Mounted to slide in the bore is a firing pin 16 having on its upper end a head 17 adapted to strike the powder cap in the seat 12 when the pin is driven upwardly. To accomplish this I 50 provide in the body of the device a hammer 55

18 pivoted as at 19, its free end 20 resting against a stop 21 where it is normally held under the action of a spring 22. On the under side of the hammer near its pivotal end is a shoulder 23 engaged by a hook 24 60 that is carried on a rod 25 extending into the body tube C. At its extremity 26 the rod connects with a spring 27 which is secured to a fixed part of the body, its tendency being to hold the hook 24 releasably 65 in engagement with the shoulder 23.

The movements of the parts described are controlled through a trigger 30 extending through a slot 31 in the body tube C for pivotal mounting therein as at 32. The 70 trigger lies just rearwardly of the rod 25 which, by a pin 33, is connected with a bolt 34 having a slotted head 35 through which the trigger is extended. Normally the trigger is maintained in a forward position 75 under the influence of a spring 36 whose ends bear respectively against the bolt head 35 and a plug 37 which is screwed into the end of the body tube.

The construction of the handle D is such 80 as to render the device adapted to be conveniently grasped for use. At its lower end the handle is chambered as at 38, a closure therefor being provided in a plate 39 having a knob 40 to facilitate its removal. Secured to the plate are four walls providing a container 41, one of these walls 42 being short so as to leave the adjoining walls 43 unsupported, by which construction they 85 tend to spring outwardly to provide a frictional connection for the retainer when fitted within the handle end, as shown.

In the operation of the present gun, the plate 10 is swung outwardly for the insertion in its seat of an ordinary powder cap 95 adapted to be ignited by percussion. After replacing the plate in operative position, a quantity of powder is spilled into the trough some of which enters the hole 13 to form a train to the percussion cap. The gun is now ready to be set off, and this may be accomplished by pulling the trigger toward the handle to draw the hammer away from the lower end of the firing pin. Continued retraction of the trigger will result in the 100 hammer being turned until its shoulder is disengaged from the rod hook, whereupon the hammer flies back under the action of its spring to kick the firing pin upwardly. This pin drops downwardly as the hammer is 110

pulled back, its head 17 finally resting on the body neck, as shown in Fig. 2. Upon being released the hammer flies back against the stop 21 whereupon the firing pin is kicked upwardly to ignite the powder cap through percussion. From this it results that the flash light powder on the trough is also ignited.

The advantages of the present construction are many, but I would have it noted particularly that the powder within the trough is sealed against contact with the operating parts by means of the powder cap which is held within the seat 12. The trigger which is normally held by the action of the spring 36 against retraction is instantly ready for service whenever necessary. Also in the handle chamber within the retainer 41 may be stored a supply of spare caps, thus obviating the necessity of having these articles carried separately.

The several parts of the device are connected by any suitable means, and may be formed in any manner which will expedite their manufacture and assembly. The apparatus may be variously modified without in any way departing from the spirit of my invention as set forth in the appended claims, and in respect of any such changes in construction, I desire that the same be included within the scope of this patent.

I claim:

1. In a flash light gun, the combination of a trough, a body on which the trough is mounted, a powder cap seat movably mounted beneath the trough, there being a hole through the trough bottom communicating with the seat and an opening therebelow into the body, a firing pin in the opening, and trigger mechanism within the body adapted to drive the firing pin against the cap to explode the same, substantially as described.

2. In a flash light gun, the combination of a body, a powder trough thereon having a hole through one of its walls, a shiftable powder cap seat adjacent the hole, and means for igniting the powder cap contained within the body including a freely movable firing pin adapted by gravity to remain remote from the cap seat, and a tension actuated device adapted for impact against the firing pin, substantially as described.

3. In a flash light gun, the combination of a trough, a body on which the trough is mounted, a powder cap seat movably arranged between the trough and body, there being a hole through the trough adjacent the seat, a firing pin mounted in the body and adapted to strike the powder cap when placed within the seat therefor, mechanism for driving the firing pin comprising a spring actuated hammer having a shoulder

thereon, a stop against which the hammer is rested when engaged with the pin, a hook bar releasably engaged with the hammer, and a trigger adapted to retract the hook bar and with it the hammer to a point where the bar and hammer are disengaged, the hammer being adapted upon release to drive the firing pin against the powder cap to explode the same, substantially as described.

4. In a flash light gun, the combination with a body, of trigger mechanism therewith including a tension actuated pivoted hammer, a slidable bar having means for connecting with the hammer through a limited movement only, means for retracting the bar and hammer through a range sufficient to disengage the one from the other, a firing pin having one end in the path of return movement of the hammer, means exteriorly of the body providing a seat for a powder cap adjacent the opposite end of the firing pin, and a trough adjacent the seat formed with an opening leading thereto, the pin being adapted to explode the powder cap to thereby ignite the powder in the trough, substantially as described.

5. In a flash light gun, the combination of a powder receptacle, means movably mounted adjacent thereto providing a seat for a powder cap, there being an opening extending from the receptacle to a point adjacent the seat when the latter is in operative position, a firing pin adapted to percuss the cap only when the seat therefor is in operative position, and means for driving the firing pin against a cap within the seat, substantially as described.

6. In a flash light gun, the combination of a powder receptacle having an opening therethrough, a firing pin adapted to be driven into proximity with the opening, means for closing the opening comprising a movable mounting adjacent thereto, and a powder cap held within the mounting, and means for driving the firing pin to percuss the cap while held within the mounting, substantially as described.

7. In a flash light gun, the combination with a powder receptacle, of means for igniting powder therein comprising a firing pin adapted to ignite the powder, a mounting therefor comprising a hollow body, and mechanism within the body adapted to drive the firing pin to operative position, said mechanism including a pivoted trigger, two interconnected parts through which the trigger is extended to lie exteriorly of the body, a spring engaging one part, and a plug removably secured to the body also engaged by the spring, substantially as described.

FRANK SCHORIK.
